his Attorney

UNITED STATES PATENT OFFICE.

FRED A. BROWN, OF LOS ANGELES, CALIFORNIA.

METHOD AND APPARATUS FOR UNLOADING POLES OR THE LIKE FROM CARS.

Application filed April 23, 1923. Serial No. 634,166.

To all whom it may concern:

Be it known that I, FRED A. BROWN, a citizen of the United States, and a resident of the city of Los Angeles, county of Los Angeles, and State of California, have invented new and useful Improvements in Methods and Apparatus for Unloading Poles or the like from Cars, of which the following is a specification.

10 This invention has to do with a method and apparatus for unloading poles, or the like, from cars, and it is an object of the invention to provide a method and apparatus by which poles can be easily, quickly and 15 safely unloaded.

Poles, and other devices and materials are commonly transported from place to place on flat cars, the poles being arranged longitudinal on the cars between stakes 20 which extend upwardly at the sides of the cars. Poles, such as are used for carrying wires, are very commonly transported in this manner, and when thus transported present the conditions under which the present invention is adapted to be used, so, 25 therefore, I will hereinafter refer to my invention as applied to a load of poles carried on a car in the manner above specified, it being understood, of course, that I do not limit the invention to this specific application, as it is applicable to various other situations of this general character.

When poles are loaded on flat cars between stakes it is usually difficult, and, in 30 many cases, dangerous to unload them. Loads of poles frequently shift so that they are leaning considerably to one side when it is desired to unload them, and in many cases, of course, they lean away from the 35 side at which it is desired to unload them, thus making it difficult to unload them. Further, the stakes used to hold the poles are of inferior material, and occasionally fail while the poles are being unloaded, making it particularly dangerous for the 40 workmen.

It is an object of this invention to provide a simple, convenient and safe method of unloading poles from a car.

45 Another object of the invention is to provide a method for unloading poles from a car which can be successfully and effectively carried out quickly and with but few men.

It is another object of this invention to provide a simple, effective and practical apparatus for carrying out the method which I have provided.

Another object of the invention is to provide various refinements and improvements in the apparatus to make it reliable, durable 60 and convenient.

The various objects and features of my invention will be best and more fully understood from the following detailed description of a typical preferred manner of carrying it out, and form of apparatus embodying it, throughout which description reference is had to the accompanying drawings, in which:

Fig. 1 is a perspective view showing a 70 typical flat car carrying a load of poles, and showing the apparatus provided by the present invention in position for unloading the poles;

Fig. 2 is an end elevation of the parts 75 shown in Fig. 1;

Fig. 3 is an enlarged detail side elevation of the outer portion of the brace member;

Fig. 4 is a plan view of the parts shown in Fig. 3;

Fig. 5 is an enlarged detail view, showing the manner in which the post of the unloading apparatus is mounted on the car, and how the brace is connected with the post.

In the drawings numeral 10 designates a 85 typical railroad car, of the type ordinarily known as a flat car. The car 10 includes a frame 11 which carries a suitable flat platform 12, and trucks 13 which support the frame 11. At suitable intervals along the 90 sides of the car 10 there are brackets 14 adapted to hold stakes, or the like, in the manner hereinafter described.

In Figs. 1 and 2 of the drawings I have shown a load of poles 15 arranged on the 95 platform 12. The poles 15 are arranged longitudinally on the platform 12 and are held between stakes 16 arranged in the brackets 14 so that they extend upwardly from the sides of the platform 12. The stakes 16 are 100 usually rough timbers having their lower ends dressed so that they more or less tightly fit into the brackets 14, and are sufficiently long to extend to the top of the load of poles. The load of poles is usually further held by 105 wires 17 which extend between the stakes at

opposite sides of the load at various points between the top and bottom of the load, as I have clearly illustrated in the drawings.

The method provided by my present invention includes backing up or bracing the load at one side, temporarily releasably tying the load, making the load free except for the releasable tie, and then gradually releasing the tie. In bracing the load from the side opposite from that at which it is to be unloaded it is impossible for the poles, when released, to fall to the wrong side of the car, and it is safe for the workmen to remain at the side of the car. By tying the load so that it is gradually releasable, it remains substantially intact, and, in any event, it remains on the car after the various supporting or bracing means provided for holding it while in transportation have been released. Upon gradually releasing the tie the load is lowered from the car gently and safely yet quickly.

The apparatus or equipment provided by my invention includes a post 20, a brace 21, a foot 22 for the brace 21, means 23 for holding the brace in position, and a tie 24 for holding the load.

The post 20 is adapted to be removably mounted on the car 10 so that it extends upwardly from the side of the platform 12 in much the same manner as a stake 16. In practice it is convenient to mount the post on the car by arranging its lower end in one of the brackets 14, provided on the car for a stake. When this manner of mounting is employed the lower end portion of the post is shaped and proportioned so that it will more or less accurately fit into the bracket 14, and means is provided for positively holding the post in place in the bracket. The post may be positively held in the bracket by arranging a pin 25 through the lower end of the post below the bracket in the manner clearly illustrated in Figs. 1 and 5. The pin 25 may be connected with the post 20 by means of a small chain 26, or the like, so that it will always be at hand when it is desired for use. This form of means for securing the post in the bracket 14 is particularly desirable in that it is secure, reliable and convenient. I ordinarily prefer to form the post 20 of wood, for instance, of an oak timber, and when it is formed of this material I preferably bind its lower portion with a metal strap 27. The strap 27 may be secured in place on or around the wooden body by suitable bolts 28, or the like. The strap 27 reinforces the post and protects it against being injured and against being worn or broken where it is carried by the bracket 14.

The brace 21 is provided to back up or support the post 20 in its upright position at the side of the load of poles. The brace 21 extends diagonally between the post 20

and the ground and is preferably connected with the post at a point about midway between its ends and is proportioned so that it extends diagonally downward to the ground at an angle of about forty degrees. The brace 21 is preferably pivotally connected with the post 20.

In the particular form of construction illustrated in the drawings, the upper end of the strap 27 at the outer side of the post 20 is turned back to form a loop 30. Plates 31 are secured to opposite sides of the upper end portion of the brace 21 so that they extend from the upper end of the brace to form two spaced arms 32. The brace is adapted to be releasably pivotally connected with the post 20 by arranging a pin 33 through the arms 32 and loop 31 in the manner illustrated in Figs. 1 and 5 of the drawings. The pin 33 is preferably tied to one of the parts, for instance, the brace 21, by a suitable flexible member or chain 34. This form of connection between the post and brace is particularly simple and effective and is easily and quickly secured and released by manipulation of the pin 33.

The foot 22 is arranged at the lower end of the brace 21, and is preferably removably mounted on the lower end of the brace so that it can be removed or replaced as circumstances may require. In accordance with the preferred form of construction, the lower end portion of the brace 21 is bound by a metal strap 35 so that the lower end of the brace will not be broken or injured when the foot is removed or upon its being used without the foot. The foot 22, which I have illustrated in the drawings, is adapted to form an effective support for the brace in soil, or the like, so, therefore, it includes a body 36 having a comparatively large flat bottom 37. Two spaced brackets 38 are provided on the body 36 to receive the lower end of the brace 21, and a pin 39 is adapted to be arranged through the brackets 38 and lower end portion of the brace 21 to secure the foot in place on the brace. It will be obvious, of course, that the foot 22 may be mounted on the brace 21 in various manners other than the one just described and that it may be constructed or designed in various manners to suit various operating conditions.

The means 23, which I have illustrated in the drawings, for holding the brace 21 in position in addition to the foot 22, includes a flexible member, for instance, a chain 40, having one end connected with the lower end portion of the brace 21 and the other end adapted to connect with a stationary part, for instance, a part of the car 10 or the track 41, on which the car is standing. In practice the outer end of the chain 40, that is, the end of the chain adapted to be connected with the stationary part, is provided with a hook 42 so that

the chain can be arranged around the stationary part, for instance, one of the rails 43 of the track 41, and made secure by arranging the hook through one of the links 5 in the manner clearly illustrated in Fig. 1 of the drawings. In accordance with my invention I provide means for adjusting the chain 40 so that it may be made tight to effectively hold the brace 21. In the form 10 of the invention illustrated in the drawings this adjustability is provided at the connection of the chain with the brace. A rod 45 is carried by the brace 21. One end of the rod 45 is provided with an eye 46 15 which carries the end of the chain, while the other end of the rod is screw threaded and carries a nut 47, preferably a wing nut. The nut 47 engages a bracket 48 mounted on the brace 21, and through which the 20 rod 45 extends. From inspection of the drawings, and particularly from Figs. 1 and 3, it will be obvious how the connection of the chain with the brace may be adjusted by rotating the nut 47 on the screw threaded end of the rod 45. In practice the chain 25 40 may be made tight so that it tightly holds the brace 21 after its outer end has been connected with a stationary part by tightening the nut 47 on the rod 45, thus 30 causing the chain to be drawn toward the brace 21.

The flexible tie 24, provided for holding the load of poles while they are being unloaded, is preferably a rope. The rope is 35 adapted to have one end secured, to be arranged around over the load of poles from the side of the car from which the poles are to be unloaded, and to have its other end releasably held at the other side of the 40 car. The end of the rope adapted to be made fast may be tied to a stationary part, for instance, to a part of the car or one 45 of the rails 43, as I have illustrated in Fig. 2. The rope is arranged around over the top 50 of the load of poles at a point about opposite the post 20 and the end which is adapted to be releasably held at the braced side 55 of the load of poles may be passed around a suitable stationary part, for instance, 60 around a part of one of the trucks 13 of the car and be held by hand. The arrangement of the rope in connection with the load 65 is clearly illustrated in Figs. 1 and 2 of the drawings.

In carrying out the method provided by 55 my invention, and in using the apparatus provided, it is usually desirable to employ two sets or units of apparatus, one at each 60 end of the load of poles. The first operation is to arrange the posts 20 in the brackets 14 and brace and secure them by means of the braces 21 and means 23. The ties 24 are then arranged around over the load 65 of poles 15 and the ends of the ties at the braced side of the load are held, for instance,

by hand. Suitable skids 60 may be arranged at the side of the car from which poles are to be unloaded to direct the poles away from the car and to prevent them from falling when they are released. While 70 the ties are held more or less tightly around the load of poles the tie wires 17 extending between the stakes 16 are cut and the stakes at the side of the car at which the poles are to be unloaded are removed, for instance, chopped away so that the poles are left held only by the posts and the ties 24. It is true, of course, that when the stakes are removed that the load may settle 75 somewhat but it cannot fall from the car so long as the ties 24 are held securely. To lower the load from the car the ties 24 are gradually released from the braced side by allowing them to slip around the parts 80 around which they are arranged. This releasement of the ties allows the load of poles to gradually lower onto the skids and to go to the ground where they can be left in a pile or moved, as desired. There will, of course, be some poles that will not pass off 85 of the car in this manner but these can be very easily removed one by one without danger. When the car has been completely 90 unloaded the units of apparatus can be easily and quickly removed and installed in connection with another car or can be handled 95 in any desired manner.

From the foregoing description it will be obvious how the present invention provides a method and apparatus by which a 100 load of poles can be easily and quickly removed from a car with very little labor and without danger to the workmen.

Having described only a typical preferred form of my invention I do not wish to limit myself to the specific details hereinabove set forth but wish to reserve to myself any changes or variations that may appear to those skilled in the art or fall within the scope of the following claims.

Having described my invention, I claim:

1. The herein-described method of unloading poles from a car on which they are held by stakes including, bracing the poles at one side of the car, tying the poles on the car, 115 releasing the stakes, and then releasing the tying.

2. The herein-described method of unloading poles from a car on which they are held by stakes including, bracing the poles at one side of the car, temporarily tying the poles on the car, and releasing the stakes while the poles are temporarily held.

3. The herein-described method of unloading poles from a car on which they are held by stakes including, bracing the poles at one side of the car, temporarily securing the poles on the car, releasing the stakes, and then releasing the temporary securing.

4. The herein-described method of unloading

ing poles from a car on which they are held by stakes including, bracing the poles at one side of the car, tying the poles on the car, releasing the stakes, and then gradually 5 releasing the tying.

5. Apparatus for use in unloading poles from a car including, a post adapted to be arranged to extend upwardly at one side of the car to hold the poles at that side of the 10 car, and a brace secured to the post and extending therefrom to the ground.

6. Apparatus for use in unloading poles from a car including, a post adapted to be arranged to extend upwardly at one side of 15 the car to hold the poles at that side of the car, a brace secured to the post to extend therefrom to the ground, and means for securing the lower end of the brace in place.

7. Apparatus for use in unloading poles 20 from a car including, a post adapted to be arranged to extend upwardly at one side of the car to hold the poles at that side of the car, a brace, and means for detachably connecting the brace with the post so that it 25 extends therefrom diagonally downwardly to the ground.

8. Apparatus for use in unloading poles from a car including, a post adapted to be arranged to extend upwardly at one side of 30 the car to hold the poles at that side of the car, a brace, and means pivotally connecting the brace with the post to extend diagonally downwardly therefrom to the ground.

9. Apparatus for use in unloading poles 35 from a car including, a post adapted to be arranged to extend upwardly at one side of the car to hold the poles at that side of the car, a brace, and means releasably pivotally connecting the brace with the post to extend 40 diagonally downwardly therefrom to the ground.

10. Apparatus for use in unloading poles from a car having brackets on its sides for stakes, or the like, including, a post adapted 45 to be mounted in one of the brackets to hold the poles at one side of the car, a pin to be arranged through the post for securing the post in place in the bracket, and means for bracing the post.

50 11. Apparatus for use in unloading poles from a car including, a post adapted to be arranged to extend upwardly at one side of the car to hold the poles at that side of the car, a brace connected with the post to extend 55 therefrom to the ground, and means for securing the brace in place including a chain having one end connected with the lower end portion of the brace and the other

end adapted to be secured to a stationary member.

60 12. Apparatus for use in unloading poles from a car including, a post adapted to be arranged to extend upwardly at one side of the car to hold the poles at that side of the car, a brace connected with the post to extend therefrom to the ground, and means for securing the brace in place including a chain having one end adapted to be connected with a stationary member and means adjustably connecting the other end of the chain with the lower portion of the brace.

65 13. Apparatus for use in unloading poles from a car including, a post adapted to be arranged to extend upwardly at one side of the car to hold the poles at that side of the car, a brace secured to the post to extend therefrom to the ground, and a foot on the lower end of the brace to engage the ground.

70 14. Apparatus for use in unloading poles from a car including, a post adapted to be arranged to extend upwardly at one side of the car to hold the poles at that side of the car, a brace connected with the post to extend therefrom to the ground, a foot, and means for detachably securing the foot on 75 the lower end of the brace.

80 15. Apparatus for use in unloading poles from a car having brackets on its sides for stakes, or the like, including, a post adapted to be mounted in one of the brackets to hold the poles at one side of the car, means for securing the post in place in the bracket, a brace, means for detachably pivotally connecting the brace with the post so that the brace extends diagonally downwardly to the ground, a foot mounted on the lower end of the brace, and a member connected with the lower portion of the brace and adapted to connect with a stationary part to secure the brace in position.

85 16. Apparatus for use in unloading poles from a car including, a post arranged to extend upwardly at one side of the car to brace the poles at that side of the car, and a flexible tie having one end secured and being arranged around over the poles so that its other end is at the same side of the car as the post and is adapted to be releasably held.

90 In witness that I claim the foregoing I have hereunto subscribed my name this 31st day of March, 1923.

100 FRED A. BROWN.
